UNITED STATES PATENT OFFICE.

EDWIN N. LIGHTFOOT, OF NEW YORK, N. Y., ASSIGNOR, BY MESNE ASSIGNMENTS, TO OTTO E. HANSEN AND SONS, OF PERTH AMBOY, NEW JERSEY, A COPARTNERSHIP CONSISTING OF MARIE HANSEN, ALBERT HANSEN, AND CARL W. HANSEN.

ELECTRIC HEATER.

Application filed January 9, 1920. Serial No. 350,385.

To all whom it may concern:

Be it known that I, EDWIN N. LIGHTFOOT, a citizen of the United States, residing at New York, in the county of Bronx and 5 State of New York, have invented new and useful Improvements in Electric Heaters, of which the following is a specification.

This invention relates to electric heaters.

It relates more particularly to heaters in 10 which the supports for the resistance elements represent clusters of logs.

An object of the invention is to provide improved means for supporting the resistance elements of such heaters.

15 Another object is to provide improved terminals for heaters of this type.

Another object is to provide an ornamental protective screen for the resistance elements of such electric heaters.

20 Another object is to provide for the resistance elements of such heaters a bed of insulation representing ashes.

Another object is to provide resilient terminals for such heaters whereby the resistance element and the fragile supports thereof are protected.

Another object is to provide improved means for anchoring the resistance elements to the support of the heater.

30 Other objects and advantages will appear from the description and claims.

An embodiment of the invention is illustrated in the accompanying drawings which are for the purpose of illustration only, for 35 it is obvious that many embodiments may be made by and will readily occur to those skilled in the art.

In the drawings:

Fig. 1 is a front elevation of an electric 40 heater in which the support for the resistance element represents a cluster of logs;

Fig. 2 is a vertical section on line 2—2 of Fig. 1;

Fig. 3 is an exploded perspective of a 45 terminal bracket to which the resistance element is connected, and of a terminal of the heater;

Fig. 4 is a vertical section through a terminal bracket with the resistance element 50 connected therewith; and

Fig. 5 is an end elevation of one of the

anchors employed for securing the resistance element to the log.

The electric heater has a support formed of terra-cotta or other suitable material to 55 represent a cluster of three logs 1, 2 and 3. The two lower logs 2 and 3 are hollow. A suitable cover plate 4 is provided for the opening in the bottom of the lower logs. The cluster of logs is provided with a plurality of feet 5 by which the heater is supported.

The front face of the cluster of logs is provided with a groove 6 which has a lining 7 of suitable insulating material such as asbestos. The outer face of the asbestos lining is composed of asbestos wool or other suitable material which represents a bed of ashes upon which the resistance element of the heater rests.

The resistance element of the heater comprises a helical coil 10 of resistance wire, which rests upon the bed of asbestos wool. The resistance coil 10 intermediate the ends thereof is anchored to the base of the groove 75 6. The means for thus anchoring the resistance coil comprises a wire loop 11. The wire follows a tortuous or zigzag path of sufficient breadth to span at least two convolutions of the resistance coil. The ends 80 of the wire 11 are twisted together thus forming a loop around the resistance coil 10. The ends of the wire 11 thus united extend through an opening 12 in the base of the groove 6. The extreme ends of the 85 wire 11 are then bent over the edges of the opening 12 thus anchoring the resistance coil 10 to the base of the groove 6. Other suitable anchoring means may, of course, be employed.

An L-shaped terminal bracket 13 is provided at each end of the groove. This bracket is secured to the cluster of logs by means of a bolt 14 extending through an opening 15 in the base of the groove 6. A 95 flexible terminal 16 is clamped between the roof of the interior of the lower log 2 by means of a nut 17 cooperating with the bolt 14.

Each end of the resistance coil 10 is connected with the adjacent terminal bracket 13. A plug 18 is inserted in the end of

the coil 10. The end of the wire is formed into a loop. This loop is clamped between the head 19 of the plug and the vertical portion of the bracket 13 by means of a screw 20 extending through an opening in the bracket 13 and having threaded engagement with the plug 18.

The resistance coil may be protected by means of an ornamental screen 22 forming a covering for the groove 6. This ornamental screen is formed of wire to represent a twig. The ends of the various arms of the twig are bent for insertion in small holes provided in the logs.

15. A pair of conductors 23 and 24 connected with a plug 25 through a Feed Through switch 26 may be connected with the respective terminals of the heater. These conductors extend through an opening provided 20 in the rear of the log 3. By means of the plug 25 the heater connected with the conductors may be connected with a suitable source of current supply.

The resistance coil 10 is plainly visible 25 throughout its length and when connected with a source of current it presents a continuous glow throughout the length of the cluster of logs. This electric heater not only furnishes heat but also furnishes light. It 30 is of pleasing appearance. The asbestos wool upon which the resistance coil rests has the appearance of a bed of ashes when the resistance coil is glowing. The protective screen representing a twig adds to the effectiveness of the electric heater in presenting a structure which closely represents an open wood fire.

What I claim is:

1. An electric heater comprising a support 40 representing a cluster of logs, said support having a groove in the front face thereof, insulating material representing ashes located in the groove, and a resistance element positioned in the groove and resting 45 on the insulating material.

2. An electric heater comprising a support representing a cluster of logs, said support having a groove in the front face thereof, insulating material forming a lining for 50 the groove and having an outer face of asbestos wool, and a resistance element positioned in the groove and resting upon the asbestos wool.

3. An electric heater comprising a support 55 representing a cluster of logs, said support having a groove in the front face thereof, insulating material forming a lining for the groove and faced with asbestos wool, and a resistance element positioned in the 60 groove.

4. An electric heater comprising a support representing a cluster of logs, said support having a groove in the front face thereof, a resistance element positioned continuously 65 within the groove and extending

through substantially the entire length thereof, and means for anchoring the resistance element to the support at points intermediate the length of the resistance element.

5. An electric heater comprising a support 70 representing a cluster of logs, said support having a groove in the front face thereof, a resistance element positioned continuously within the groove and extending through substantially the entire length thereof, and anchoring means encircling the resistance element at points intermediate the length thereof and cooperating with the base of the groove for attaching the resistance element thereto.

6. An electric heater comprising a support 75 representing a cluster of logs, said support having a groove in the front face thereof, a terminal bracket at each end of the groove, a resistance element positioned within the groove and connected with the terminal brackets, resilient terminals for the heater, and means for securing the terminals to the respective brackets and for securing the brackets and terminals to the support.

7. An electric heater comprising a support 80 representing a cluster of logs, said support having a groove in the front face thereof, a resistance element positioned continuously within the groove, and an ornamental protecting screen for the resistance element forming a covering for the groove and representing a twig.

8. An electric heater comprising a support 85 representing a cluster of logs, said support having a groove in the front face thereof, a bed of insulating material located within the groove and representing ashes, a resistance element positioned within the groove upon the bed of insulating material, and an ornamental protecting screen for the resistance element forming a covering for the groove and representing a twig.

9. An electric heater comprising a support, a terminal bracket secured to the support, a resistor formed into a helical coil, a plug inserted in one end of the coil, and means for fastening the plug to the bracket with the attached end of the resistor clamped therebetween.

10. An electric heater comprising a support 100 representing a cluster of logs, said support having a groove in the front face thereof, a terminal bracket at each end of the groove, a resistance element positioned within the groove and connected with the terminal brackets, a bolt for securing each bracket to the support and extending through an aperture therein, and means for connecting electric conductors to the bolts.

In witness whereof, I have hereunto subscribed my name.

EDWIN N. LIGHTFOOT.
